CLAIM

The ornamental design for a card case, as shown and described.

DESCRIPTION

FIG. 1 is a front perspective view of a card case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the usage state diagram.

The broken lines shown traveling across claimed surfaces depict stitching and form a part of the claim. The broken lines shown surrounding portions without any surface shading depict portions of the article and form no part of the claim.

1 Claim, 9 Drawing Sheets(56)
